UNITED STATES PATENT OFFICE.

NICHOLAS I. ALLEN, OF ROCHESTER, NEW YORK, ASSIGNOR TO IRVING W. VAN ZANDT, OF SAME PLACE.

BELT-LACE.

SPECIFICATION forming part of Letters Patent No. 313,974, dated March 17, 1885.

Application filed April 18, 1884. (No model)

To all whom it may concern:

Be it known that I, NICHOLAS I. ALLEN, of Rochester, Monroe county, New York, have invented a certain new and useful Improvement 5 in Belt-Laces; and I do hereby declare that the following is a full, clear, and exact description of the same, reference being had to the accompanying drawings, in which—

Figure 1 is a plan view of the lace. Fig. 2 is a cross-section on an enlarged scale. Fig. 3 is a plan view of the meeting ends of a belt with the lacing in place. Fig. 4 is a longitudinal section of the same.

My improvement relates to a belt-lace made 15 from lamp-wicking or equivalent fibrous fabric woven, knit, or braided together with strands of wire therein to prevent stretching, the lace when complete to be treated with a preparation of liquid asphaltum or coal-tar, 20 which imparts hardness and smoothness to enable it to be drawn through the lace-holes easily, and also gives it additional strength, all as hereinafter described.

In the drawings, A shows the lace, which is 25 made of woven, knit, or braided fabric similar to lamp-wicking. In the act of making, several strands of small wire, *a a*, are embodied in the lace, which strands extend longitudinally, as shown. These strands are so small as 30 to be flexible and not interfere with the bending of the lace when inserted in the belt, yet they are so strong and unyielding lengthwise that they effectually prevent stretching in a

great degree, and obviate the loosening of the joint of the belt. Thus prepared the lace is 35 dipped into or otherwise treated with liquid asphaltum or coal-tar, which saturates the whole fibrous mass, and has the effect of smoothing and hardening the whole body and laying the surface, so that in drawing through 40 the lacing-holes there is no impediment, as there would be if the lace were dry and the fibers stood up on the surface. It also gives additional strength to the lace.

This lace is designed to be used in place of 45 the ordinary leather thong and in the same manner, and is not only much cheaper, but it is much stronger and will last longer.

b b are metallic tips at the ends of the lace to facilitate the insertion of the lace through 50 the lacing-holes.

What I claim as new, and desire to secure by Letters Patent, is—

A belt-lace made of lamp-wick treated with asphaltum or coal-tar, provided with metallic 55 tips at its ends, and having strands of wire running longitudinally through the lace, as and for the purpose specified.

In witness whereof I have hereunto signed my name in the presence of two subscribing 60 witnesses.

NICHOLAS I. ALLEN.
